DECK LID HINGE

John H. Roethel, Detroit, Mich., assignor to
 Marvel Equipment Corporation, Detroit, Mich.,
 a corporation of Michigan

Application December 19, 1940, Serial No. 370,783

10 Claims. (Cl. 16—135)

This invention relates to hinges particularly adapted for pivotally connecting together a swinging closure and a fixed body or support, the hinge of the present invention being especially useful in connection with swinging doors or lids of vehicle bodies, such as trunk, hood or deck lids of motor vehicles.

An object of the invention is to provide a hinge for an upwardly swinging closure or lid which is provided with improved relatively simple, efficient and economical spring controlled means for holding the lid or closure in a raised position, such means being operated simply by manipulating the lid in raising and lowering the same.

Another object of the invention is to provide a hinge for a swinging closure or lid having an improved counterbalancing spring device held substantially out of operation, or in a condition to exert immaterial resistance to the raising of the lid or closure during a part of its movement and thereafter effective to exert a substantial effort or force to move the lid and hold it, or assist in holding it, in fully raised position.

A further object is to provide a hinge having a counterbalancing spring for holding the closure in raised position and rotatable means actuated by the movement of the closure for controlling the tension or resistance of the spring effective to raise the closure.

A further object of the invention is to provide an improved hinge structure for a swinging lid or closure, especially of the foregoing type, comprising a pair of hinge members secured to the lid and which are pivoted on a common transverse axis to swing in parallelism, the hinge members being connected through parallel links eccentrically to separate pre-loaded springs arranged on a common axis parallel to the axis of swinging of the hinge members, the construction being such that the effective effort in unison of the springs at or near the closing position of the lid is minimized whereas the effective lifting effort of the springs at and near the fully open position of the lid is increased.

Other objects of this invention will appear in the following description and appended claims, reference being had to the accompanying drawings forming a part of this specification wherein like reference characters designate corresponding parts in the several views.

Fig. 1 is a fragmentary perspective view of the rear end of an automobile body illustrating a lid or closure hinged to the body by means of a hinge device constructed in accordance with the present invention.

Fig. 2 is an enlarged vertical section taken substantially through lines 2—2 of Fig. 1 looking in the direction of the arrows.

Fig. 3 is a section taken substantially through lines 3—3 of Fig. 2 looking in the direction of the arrows.

Fig. 4 is a section taken substantially through lines 4—4 of Fig. 2 looking in the direction of the arrows.

10 Fig. 5 is a fragmentary view partly similar to Fig. 4 but illustrating another embodiment of the invention.

Fig. 6 is a section taken substantially through lines 6—6 of Fig. 5 looking in the direction of the arrows.

15 Fig. 7 is a section taken substantially through lines 7—7 of Fig. 6 looking in the direction of the arrows.

20 Before explaining in detail the present invention it is to be understood that the invention is not limited in its application to the details of construction and arrangement of parts illustrated in the accompanying drawings, since the invention is capable of other embodiments and 25 of being practiced or carried out in various ways. Also it is to be understood that the phraseology or terminology employed herein is for the purpose of description and not of limitation.

20 In the drawings there is illustrated, by way of example, a hinge or hinge structure embodying the present invention as applied to a swinging closure, such as the deck lid or trunk lid or the like of an automobile body. It will be understood that the hinge of the present invention may be 30 utilized in connection with other closures such, for example, as the swinging hood lid of a vehicle body and further it is to be understood that, although in the present instance the hinge is illustrated as arranged in a particular manner, yet other arrangements and other positioning of the hinge including the support thereof and other parts may be resorted to without departing from the invention.

35 In the embodiments of the invention herein illustrated, by way of example, the hinge structure is applied to an automobile body A which has a rear metal panel B forming a sloping deck, trunk or other compartment provided with an opening C into the compartment which is adapted 40 to be closed by means of a swinging lid or closure member 10. It will be seen that the lid or closure 10 is bowed or curved transversely and in the present instance the hinge members connected to the lid are arranged near the middle 45 of the upper edge of the deck lid at the highest

point of the upper edge of the opening C of the compartment.

Referring to Figs. 1 to 4 inclusive, the hinge structure of this embodiment comprises a pair of similar hinge members or arms 11 and 111 of generally goose-neck construction so as to swing about and clear the upper edge of the compartment opening C, as clearly seen in Fig. 2. The hinge members 11 and 111 are provided at their outer ends with flanges 11a and 111a, respectively, and these flanges are secured as by rivets 11b to the underface of the deck lid 10 adjacent the upper edge thereof. The present hinge structure includes a supporting frame generally indicated by the numeral 12, this frame being of skeleton construction and generally rectangular in shape and composed of four pressed metal sections. As illustrated the frame in the present instance comprises a front transverse section 13, a rear section 14 similar and parallel thereto, and parallel end sections 15. The section 14 is provided with flanges 14a at opposite ends which are secured, as by spot welding, to depending flanges 15a on the end sections 15. In like manner the front section 13 of the frame is provided with depending end flanges 13a secured, as by spot welding, to the depending flanges 15a of the end sections. The several sections of the skeleton frame may be provided with suitable embossings 13b, 14b and 15b for the purposes of reenforcement and, as illustrated, the horizontal flanges of the end frame sections 15, which have longitudinal embossments 15b, are provided with apertures 15c for the reception of bolts or the like 16 by means of which the supporting frame 12 may be secured to the body within the upper portion of the deck lid compartment, as clearly seen in Fig. 2.

The hinge arms 11 and 111 are pivoted or hinged through the medium of hinge pins or studs 17 to the end flanges 13a and 15a of the skeleton frame. These hinge arms are preferably identical and each has a generally bell crank extension 11c to which is pivoted at 19 the forward end of a link 18. The rear end of the link is pivoted at 20 to a swinging arm 21 which for convenience may be termed a crank or lever arm. The crank arms 21, each of which is connected through a link 18 to one of the hinge arms, are mounted upon a fixed transverse rod 22 which is secured against rotation in apertures in the depending flanges 14a and 15a, the ends of the rod being riveted over at 22a as illustrated in Fig. 3. Each crank arm 21 has an integral hub 23 journaled to rotate on the rod 22. Each hub 23 is provided with an external helical thread-like groove. The crank arm hub 23, which is connected to the hinge arm 11, is threaded or screwed into one end of a coil spring 24. Pinned at 26 to the rod 22 centrally thereof is a collar or sleeve 25. One portion 25a of this collar is provided with an exterior helical groove threaded into the opposite end of the spring 24. The opposite side 25b of the collar 25 is provided with an exterior helical groove threaded into one end of a coil spring 27. The opposite end of the spring 27 is threaded into a hub 23 formed as a part of the link or lever arm 21 which is connected through link 18 with the hinge arm 111. The pitch of the convolutions of the spring 24 corresponds to the pitch of the exterior threads formed on the collar portion 25a and the adjacent hub 23. In like manner, the pitch of the convolutions of spring 27 corresponds to the exterior threads formed on the collar portion 25b and the adjacent hub 23 threaded into the ends of the spring

27. The springs 24 and 27 are preferably of the same size and strength with the exception that one is reversed with respect to the other and, hence, the threaded portions fitting into the ends 5 of the spring 24 are opposite to the threaded portions fitting into the ends of the spring 27, the threads in one instance being lefthand and the threads in the other instance being righthand.

In the embodiment illustrated in Figs. 5 and 6 10 the construction is substantially the same as above described with the exception that the parallel links 18 connected to the hinge arms 11 and 111 are pivoted at their rear ends at 28 to parallel swinging crank or lever arms 29 which in turn are secured to pivot pins or studs 30 journalled in the flange portions 14a and 15a of the supporting frame. Each stud 30 has a slot or kerf 31 into which the end 32a of a coil spring 32 is anchored. The opposite end 32b of each 20 spring is anchored to a lug or tongue 33 struck out from the metal of the frame. Each spring 32 of this embodiment is of the clock type comprising a flat metal strip wound spirally to provide overlying convolutions. The springs 32 differ from the coil springs 24 and 27 of the previous embodiment in that the latter have helically wound convolutions.

In the embodiment of Figs. 1 to 4 inclusive, as also in the embodiment of Figs. 5 to 7 inclusive, 30 the springs are mounted on a common transverse axis parallel to the common axis of turning of the hinge arms 11 and 111 and coincident with the axis of swinging of the crank or lever arms. As the crank arms swing during raising and lowering of the lid 10, this movement will result in partially winding or unwinding the springs varying the loaded or stressed condition thereof.

Having first selected springs of the proper size and strength to accommodate the weight of the 40 lid, the springs are assembled in pre-stressed or pre-loaded condition so as to substantially balance the weight of the lid. In the first embodiment the ends of the springs 24 and 27 are screwed onto the threaded members 23 and 25 and properly pre-loaded. Likewise the clock-type springs 32 of the second embodiment are wound so that when their ends are anchored these springs will be pre-loaded. During operation of the lid the action of lever or crank arms 21 and 29 will be to vary or permit variance in the effective effort exerted by the springs at different positions of the lid. In full lines in Figs. 2 and 6 the fully elevated position of the lid and the relation of the parts connected to the springs is indicated at Z. This position of the lid may be governed by stops 34 adapted to be engaged by the hinge arms. As the lid is lowered pivot 19 moves toward the dead center line passing through points 17 and 20 or 17 and 28, and until position Y is reached a progressive loading of the springs occurs. Beyond the dead center position and as pivot 19 moves to position X, at which time the lid is fully closed, a slight reverse action of the springs occurs in which a slight amount of effort of the springs is exerted to urge or hold the lid closed. The reverse action takes place as the lid is raised. During the initial lifting of the lid little effort is required to raise it to the position represented by dotted line dead center position Y of the linkage. Thereafter the springs exert a lifting action which tends to complete the raising of the lid and holding it in fully elevated position. In the first embodiment, when the crank arms 21 swing about the axis of coil 50 springs 24 and 27, the threaded portions 23 tend

to be screwed further into or slightly out of the ends of the springs, thus winding up or unwinding the springs to the necessary amount to secure the desired action.

I claim:

1. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, said hinge arms having crank portions projecting laterally from said axis, a pair of separate springs having their respective convolutions arranged on substantially a common axis, and means operatively connecting said hinge arms to said springs to vary the effort exerted by the springs on the lid as the latter is swung, said last means including members pivotally connected to the crank portions of said arms at points spaced from the pivotal axis of the arms and eccentrically connected to the springs at points more remote from said axis than from said points of connection of the members to the arms when the lid is closed.

2. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of separate springs having their respective convolutions arranged on substantially a common axis, and means operatively connecting said hinge arms to said springs to vary the effort exerted by the springs on the lid as the latter is swung, said last means including substantially parallel links pivotally connected to the hinge arms at points spaced from the pivots thereof and rotatively connected to the springs at points more remote from said first named axis than from the said points of connection of the links to the hinge arms when the lid is closed.

3. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of separate spirally wound springs having their respective convolutions arranged on substantially a common axis, and means operatively connecting said hinge arms to said springs to vary the effort exerted by the springs on the lid as the latter is swung, the points of connection of said means to said springs being further from the axis of the arms than from the points of connection of said means to said arms in the closed position of the lid.

4. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of separate springs having their respective convolutions arranged on substantially a common axis, and means operatively connecting said hinge arms to said springs to vary the effort exerted by the springs on the lid as the latter is swung, said springs having helically arranged convolutions and the connections between the hinge arms

and the springs including members having reversely threaded portions engaging the convolutions of the respective springs.

5. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of coil springs arranged end to end, a transverse rod extending through the springs, and means operatively connecting the hinge arms to the springs including members pivotally mounted on said rod and connected to the remote ends of the springs.

6. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of coil springs arranged end to end, a transverse rod extending through the springs, and means operatively connecting the hinge arms to the springs including members pivotally mounted on said rod and having reversely threaded connections with the remote ends of the springs.

7. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, said hinge arms having crank portions extending laterally from said axis, a pair of spirally wound springs mounted on the supporting means and arranged on a common transverse axis substantially parallel to said first mentioned axis, and lever means connecting the crank portions of said hinge arms to said springs at points lying substantially at the said axis of said springs, the points of connection of the lever means to said springs being further from the axis of the hinge arms than from the points of connection of the lever means to said crank portions in the closed position of the lid.

8. A hinge structure for a swinging lid or closure adapted to be swung between open and closed positions, comprising fixed supporting means, a pair of hinge arms adapted to be fixed adjacent their outer ends to the lid and pivoted at their inner ends to the supporting means to swing about a common transverse axis, a pair of coil springs arranged end to end, a transverse rod extending through the springs, means operatively connecting the hinge arms to the springs including members pivotally mounted on said rod and having reversely threaded connections with the remote ends of the springs, and means on said rod having threaded connections with the adjacent ends of said springs internally thereof.

9. A hinge structure for a swinging lid or closure adapted to be raised and lowered to open and close an opening, comprising a fixed support, a hinge arm fixed at one end to the lid and pivoted at its opposite end to the support, said hinge arm having a crank portion extending laterally from said pivot, a spring connected to the support, and a member pivoted to the crank portion of the hinge arm at a point spaced from the pivot of the arm and having means connected to the spring to vary the effort exerted by the

spring on the lid as the latter is swung, the pivot of the member with the hinge arm being adapted to move to opposite sides of a dead center line passing through the axis of swinging of the hinge arm and the point of connection of said means to the member, the point of connection of said means to the spring in the closed position of the lid being further from the pivotal axis of the hinge arm than from the point of pivotal connection of the member to said crank portion.

10. A hinge structure for a swinging lid or closure adapted to be raised and lowered to open and close an opening, comprising a fixed sup-

port, a hinge arm fixed at one end to the lid and pivoted at its opposite end to the support, a spring connected to the support, and means including a member pivoted to the hinge arm at a point spaced from the pivot of the arm and having means for connection to the spring to vary the effort exerted by the spring on the lid as the latter is swung, the point of connection of said means to the spring in the closed position of the lid being further from the pivotal axis of the hinge arm than from the point of pivotal connection of the member to the hinge arm.

JOHN H. ROETHEL.
